UNITED STATES PATENT OFFICE.

JACOB P. TIRRELL, OF SOMERVILLE, ASSIGNOR TO GEORGE F. PINKHAM,
OF QUINCY, MASSACHUSETTS.

ELECTRIC GAS-LIGHTING APPARATUS.

SPECIFICATION forming part of Letters Patent No. 230,589, dated July 27, 1880.

Application filed May 22, 1880. (No model.)

To all whom it may concern:

Be it known that I, JACOB P. TIRRELL, a citizen of the United States, residing at Somerville, in the county of Middlesex and State of Massachusetts, have invented certain Improvements in Electric Gas-Lighting Apparatus, of which the following is a full, clear, and exact description, reference being had to the accompanying drawings, making part of this specification, in which—

Figure 1 is a perspective view of my improved electric gas-lighting apparatus, the cover or outer casing being removed. Fig. 2 is an elevation of the same, (enlarged.) Fig. 3 is a vertical section through the center of the same. Fig. 4 is a horizontal section on the line $x-x$ of Fig. 2. Fig. 5 is a horizontal section on the line $y-y$ of Fig. 2. Fig. 6 is a perspective view of the cam which operates the circuit-breaker and switch. Fig. 7 is a perspective view of the circuit-breaker and switch and its operating-cam. Fig. 8 is a perspective view of the conical plug of the gas-valve. Fig. 9 is an elevation (on a reduced scale) of the cover or outer casing of the apparatus.

My present invention relates to that class of apparatus in which two separate wires are employed, one for letting on and lighting and the other for shutting off the gas, and has for its object to provide a neat, simple, and compact apparatus, which, on account of the small space which it occupies, is particularly adapted for use in chandeliers and brackets, as it is entirely concealed from view by the ordinary shade or globe placed over the burner.

My invention consists in the employment of a combined circuit-breaker and switch of peculiar construction, operated automatically by a cam connected with the rotary gas-valve, by means of which the electric current is caused to pass alternately by separate wires to the electro-magnet for the purpose of letting on and simultaneously lighting the gas and shutting off the same, the circuit being completed, as usual, by means of keys or pressure-buttons, which are operated alternately to let on and shut off the gas.

To enable others skilled in the art to understand and use my invention, I will proceed to

describe the manner in which I have carried 50 it out.

In the said drawings, A represents the framework of the apparatus, consisting of two disks, a , b , united by a tube, c , which serves as a conduit for the gas to the burner d , projecting from the upper disk, a . Within the bottom of the burner is fitted the vertical tapering or conical plug e of the gas-valve, which is made hollow and open at its upper end, and is provided with two narrow ports or slots, 12 , placed 60 opposite each other, which communicate with the interior of the plug, and are successively brought into line with a port, 14 , through which the gas passes from the pipe c , so that a quarter-revolution of the plug will cause the gas 65 to be let on or shut off, as required. To the bottom of this vertical plug e is secured a ratchet-wheel, B , which is arranged in a horizontal position, as seen in Figs. 2, 3, and 5, and is rotated to actuate the valve-plug e by means 70 of a spring-pawl, f , secured to a lever, C , which is pivoted to the frame-work at g , and carries the armature h of an electro-magnet, D , which is secured to the tube c and arranged between the disks a , b , a spring, i , bearing on a rod, k , 75 projecting from the lever C , serving to withdraw the armature h from the magnet when the latter is demagnetized, and thus as the lever C is vibrated in opposite directions by the magnet and spring the gas-valve is rotated to 80 let on or shut off the gas.

l is the stationary or fixed electrode, which is mounted on an arm projecting from a divided metallic collar, m , embracing the burner near the tip, the ends of this collar being provided with outwardly-projecting lugs 85 15 , 16 , through which passes the horizontal clamping-screw 17 , which engages with a screw-thread in the lug 16 ; and by means of this screw the collar is clamped firmly to the burner to hold 90 the fixed electrode in its proper position, this collar also serving to confine tightly in place a sleeve, p , of mica or other suitable insulating material, which is interposed between the collar m and the burner to insulate the fixed 95 electrode, which is connected, by means of a wire, q , with the electro-magnet. The end of the wire q is confined in place by a nut, r ,

turned over the end of the screw 17, the wire being held between the nut and the lug 16, which arrangement facilitates its attachment or detachment. The collar thus serves as a means of attachment for the fixed electrode, and also as a clamp for securely holding in place the mica insulating-sleeve *p*, this substance being specially adapted for the purpose on account of its capability of resisting the action of the heat to which it is subjected on account of its close proximity to the flame issuing from the tip of the burner.

The construction and arrangement of the collar, with its horizontal clamping-screw *m*, prevent the point of the screw from coming into contact with the mica sleeve *p*, whereas if an ordinary collar were used having the usual set-screw tapped through it the point of the screw would be liable to penetrate the mica and make a contact with the burner, which would destroy the insulation.

To a post, *t*, on one side of the burner is pivoted a lever, *u*, which carries the movable electrode *a'*, this lever, through the frame-work *A* and the gas-pipe, being connected with the battery.

The lower end of the lever *u* is slotted or bifurcated, and embraces a pin, *b'*, projecting from the lever *C*, so that when the armature is attracted to the magnet the lever *u* is vibrated, so as to separate the electrodes *l a'*, thus breaking the electric circuit and causing the spring *i* to withdraw the armature from the magnet, when the lever *u* will be moved so as to again bring the electrodes into contact, an automatic circuit-breaker being thus provided, which will keep the lever *C* constantly vibrating until the circuit is broken through the wire leading to the electro-magnet, as will be hereinafter described; and thus as the lever *u* is vibrated the electrical contact between the electrodes *l a'* is made and broken to produce the sparks to ignite the gas issuing from the orifice at the tip of the burner when the valve *e* is turned by the action of the ratchet-wheel and pawl, as above described.

The distance between the bifurcations at the lower end of the lever *u* is greater than the diameter of the pin *b'* embraced thereby, so as to allow of a lost motion, which enables the armature to have a more extended movement toward and from the magnet, thus increasing the range of the lever *C*, which increases the size and intensity of the electric spark, and also accelerates the rotation of the ratchet-wheel *B* and valve connected therewith.

The lever *u* is provided at its fulcrum with a spring-washer, 21, which insures the requisite friction at this point to retain the lever in place during the lost motion of the pin *b'* in the slot at the bottom of the lever.

I will now proceed to describe the manner in which the electric current is caused to pass through the apparatus for the purpose of rotating the ratchet-wheel *B* to open the gas-valve and simultaneously ignite the gas and

close the valve to extinguish it at the required times.

b'' c' are two separate wires, which can be connected with the same pole of the battery 70 by pressing keys or buttons, (not shown,) as usual in apparatus of this description, these pressure-buttons being located in any convenient and accessible position within the house or apartment thereof where the burner is located. The gas-valve being closed, the current, on the proper button being pressed, enters the apparatus by the wire *b''*, through which it passes to a light curved spring, *d'*, secured to an insulating-block, *E*. The outer 80 end of the spring *d'* is at this time pressed by one of two projecting portions, *e'* of a cam, *G*, (composed of hard rubber or other suitable non-conducting material, and secured to the stem of the plug *e* beneath the ratchet-wheel 85 *B*.) against a pin, *f'*, projecting from the upper side of a spring-arm, *g'*, the outer end of which is secured within the block *E*, and is in contact with a wire, *h'*, connected with the electro-magnet *D*. The current now passes through 90 the electro-magnet, and by the wire *q* to the electrodes *l a'*, and thence by the frame-work *A* to the gas-pipe and back to the battery, thus completing the circuit. The ratchet-wheel is now rotated by the vibrations of the lever *C*, 95 which follow each other in rapid succession, until the plug *e* has been turned a quarter of a revolution, which opens the gas-valve to its full extent, the gas escaping at the tip of the burner having been during the opening of 100 the valve ignited by the sparks produced by the alternate separation and contact of the electrodes *l a'*, as before described. The instant the plug *e* has completed a quarter-revolution the end of the spring *d'* drops into one 105 of the two spaces or notches *i* between the two projections *e'* of the cam, which breaks the contact between the end of the spring *d'* and the pin *f'*, one of two projections, *k'*, on the lower portion of the cam *G* being simultaneously brought into contact with another curved spring, *l'*, similar to *d'*, and also secured to the insulating-block *E*, by which means the end of the spring *l'* is pressed into contact 115 with a pin, *m'*, projecting from the lower side of the arm *g'*. The circuit through the wire *b''* is thus automatically broken as soon as the gas-valve is opened to its full extent and the gas lighted, after which the operator removes his finger from the pressure button or key of 120 the wire *b''*.

It will be seen that the armature of the electro-magnet cannot be again set in motion when it is desired to extinguish the gas by a current passing through the wire *b''*, on account of the circuit having been broken, as above described. The other wire, *c'*, is therefore employed, through which (on pressing its button) the current passes to the spring *l'*, and thence, by the pin *m'* and arm *g'*, to the wire 130 *h'* and electro-magnet, after which it takes the same course as previously described, causing

the ratchet-wheel and plug *e* to be again rotated a quarter of a revolution, and extinguishing the gas as required.

On the completion of this movement the 5 end of the spring *l*' drops into one of the two notches or spaces *p*' between the two projections *k*' of the cam *G*, which breaks the contact between the spring *l*' and the pin *m*', thus automatically breaking the electric circuit 10 through the wire *c*', after which the operator releases the button or key belonging thereto. This latter movement of the cam *G* again causes one of its projections, *e*', to press the spring *d*' into contact with the pin *f*', when the 15 electro-magnet is again connected with the wire *b*'' through which the electric current can be again passed when the gas is to be lighted; and it will thus be seen that when, by the rotation of the cam *G*, the circuit is broken 20 through the wire *b*'' the switch is operated so as to have the electro-magnet connected with the other wire, *c*', and when the magnet is disconnected from the wire *c*' it is at the same instant connected with the wire *b*'', the wires 25 *b*'' *c*' being thus used alternately, as above described, one to carry the current for opening the gas-valve and the other the current for closing it.

The plug *e*, ratchet-wheel *B*, and cam *G* are 30 supported and kept in place by a light spring, *q*', which is secured to the tube *c* and bears against the under side of the stem of the plug *e*, below the cam.

The length of the spaces *i* *p*' is the same as 35 that of the projections *e*' *k*', the upper projections, *e*', being in line with the lower spaces, *p*', and the upper spaces, *i*', being in line with the lower projections, *k*', as seen in Fig. 6.

The above-described combined circuit-breaker and switch is simple, and not liable to get 40 out of order, and occupies very little space, while the gas-valve is placed in close proximity with the orifice at the tip of the burner, so that the gas is enabled to issue therefrom 45 almost as soon as the sparks are produced, thereby rendering the ignition of the gas more certain. Furthermore, the arrangement of the horizontal ratchet-wheel, the cam *G*, and circuit-breaker and switch operated thereby is

such as to greatly economize space and enable 50 me to produce an exceedingly neat and compact apparatus, which is provided with a sheet-metal cover or casing, *H*, Figs. 3 and 9, which serves to exclude dust and moisture.

What I claim as my invention, and desire 55 to secure by Letters Patent, is—

1. In an electric gas-lighting apparatus, the combination, with the valve-plug *e* and its actuating mechanism, of the automatic switch and circuit-breaker, consisting, essentially, of 60 the cam *G*, with its projections *e*' *k*' and spaces or notches *i*' *p*', the springs *d*' *l*', with their connecting-wires *b*' *c*', and the arm *g*', with its pins *f*' *m*' and connecting-wire *h*', whereby the electric current is caused to pass alternately, 65 by the wires *b*' *c*', to the electro-magnet *D*, for the purpose of letting on and simultaneously lighting the gas and afterward extinguishing the same, substantially as set forth.

2. The combination, with the valve-plug *e* 70 and horizontal ratchet-wheel *B*, of the switch-operating cam *G*, arranged beneath and in line with the plug *e*, and connected therewith, substantially as and for the purpose set forth.

3. The combination, with the burner *d*, valve-plug *e*, horizontal ratchet-wheel *B*, operated 75 by the pawl *f*, cam *G*, and switch operated thereby, and the connecting-wires *b*' *c*' *h*' *q*', of the fixed electrode *l* and the vibrating electrode *a*', the latter attached to the lever *u*, the lower 80 end of which embraces a pin, *b*', on the lever *C*, carrying the armature of the electro-magnet, all constructed and arranged to operate together substantially in the manner and for the purpose set forth. 85

4. The combination, with the burner *d* and electro-magnet *D*, of the vertical valve-plug *e*, horizontal ratchet-wheel *B*, cam *G*, and the switch operated thereby, arranged between the burner and the electro-magnet to economize space, substantially as described. 90

Witness my hand this 12th day of May, A. D. 1880.

JACOB P. TIRRELL.
